UNITED STATES PATENT OFFICE.

ARTHUR MERTON PARKER, OF MEXICO, PENNSYLVANIA.

COMBINATION-TOOL.

SPECIFICATION forming part of Letters Patent No. 789,103, dated May 2, 1905.

Application filed March 26, 1903. Serial No. 149,683.

To all whom it may concern:

Be it known that I, ARTHUR MERTON PARKER, a citizen of the United States, residing at Mexico, in the county of Juniata and State 5 of Pennsylvania, have invented a new and useful Improvement in Combination-Tools, of which the following is a specification.

My invention relates to improvements in combination-tools in which the stock or handle o is constructed to form parts of the tools attached thereto; and the object of my improvement is to provide in an article of manufacture a combination can-opener with a corkscrew locking device, as part of a kitchen-tool. 5 I attain this object by the novel features of construction herein described, and illustrated in the accompanying drawings, in which—

Figure 1 is a bottom plan of my improvement, showing a knife-sharpener, glass cutter o and breaker, attached at one end of the stock, forming convenient auxiliary devices. Fig. 2 is a perspective view of the opposite side of the structure shown in Fig. 1, illustrating the manner in which the convolutions of the corkscrew are utilized as a means for locking the can-opener blade upon the shank. 5

Similar letters refer to similar parts throughout both views.

The stock *a* comprises the glass-cutter and o sharpener, which form the handle *b* for the combination corkscrew and can-opener, and the shank *c*, having the longitudinal groove *d*, and the perforating-point *e*. The can-opener knife *f*, having the laterally-extending blade *g*, is mounted on the shank *c*, preferably by means of its bent-over edges *h h*, and is adapted to slide along the said shank. The corkscrew *i* is pivoted to the shank *c* and

normally lies in the longitudinal groove *d*, formed therein. The convolutions of the corkscrew, as shown in Fig. 2, press against the bottom sides of the groove and form spaces which act to retain the bent-over edges *h h* of the knife *f* against longitudinal movement. It is then seen that for each convolution of 45 the corkscrew a locking position for the can-opener is formed.

To open cans, insert point *e* in top of can, adjust the knife *f* upon the shank *c* to a position that it may be locked by the corkscrew *i*, 50 press the blade *g* through the tin, and turn until the opening is accomplished. To draw corks, turn the corkscrew at an angle to the stock and use in the usual manner.

Having thus described my invention, I claim 55 and desire to secure by Letters Patent—

1. In a combination-tool, a handle carrying a shank provided with a longitudinal groove and a perforating-point, a knife slidably mounted upon the shank, a corkscrew pivoted 60 at one end of and lying in the groove and adapted to lock the knife in its several positions of adjustment.

2. In a combination-tool having a shank provided with a perforating-point, a knife slidably 65 mounted upon the shank, a corkscrew pivoted on and lying upon the shank adapted to lock the knife in its several positions of adjustment.

In testimony whereof I have signed my name to this specification in the presence of two sub- 70 scribing witnesses.

ARTHUR MERTON PARKER.
